UNITED STATES PATENT OFFICE.

ELIZABETH J. DOUGLAS, OF LOS ANGELES, CALIFORNIA.

FOLDING BOOTH.

1,071,896.

Specification of Letters Patent.

Patented Sept. 2, 1913.

Application filed July 8, 1912. Serial No. 708,120.

To all whom it may concern:

Be it known that I, ELIZABETH J. DOUGLAS, a citizen of the United States, residing at Los Angeles, county of Los Angeles, State 5 of California, have invented new and useful Improvements in Folding Booths, of which the following is a specification.

This invention relates to collapsible booths adapted for use as voting booths or for any 10 similar use; and relates particularly to certain improvements in and to the invention for which Letters Patent #828935 was issued August 21st, 1906 to Albert L. Johnson and myself.

15 The prime object of the present invention is the provision of a collapsible or folding booth structure which will stand on and about a single vertical standard, forming a plurality of private voting compartments 20 thereabout, and folding up against this standard to make a flat member of a minimum length.

25 There are several advantages of my present construction; prime among which are the simplicity of manufacture and operation of setting up, the small number of parts required, and the general efficiency of the booth in that a maximum number of compartments are provided with a minimum 30 complication of structure. In addition to these prime features, there are several subsidiary features which I will explain in the following specification, reference being had to the accompanying drawings, in which;

35 Figure 1 is a perspective showing my improved booth partly set up. Fig. 2 is a sectional plan of the same showing the booth completely set up. Fig. 3 is a detail section taken as indicated by lines 3-3 of Fig. 1. 40 Fig. 4 is a detail perspective showing one method of securing parts of the structure together. Fig. 5 is a detail perspective showing another method of securing parts of the structure together. Fig. 6 is a detail section 45 taken as indicated by line 6-6 on Fig. 1, illustrating the brace construction in the lower part of my structure.

In the drawings 10 designates an upright 50 standard which is preferably made in cruciform section, as is best shown in Figs. 1 and 2; affording four different longitudinal vertical flanges to which the various folding parts of the structure may be attached. This upright standard may be somewhat over 55 three feet in length, providing for a total height of the booths of about six feet.

Standard 10 is supported at its lower end by four legs 11 which are slidably pivoted at 12 to the lower end of the standard, one of the legs being secured to each of the 60 flanges of the standard. A suitable rivet 12 is secured in the flange and a slot 13 in the upper end of the leg engages the rivet, so that the leg may be moved longitudinally 65 as well as moved pivotally. This provides that the diagonal end 14 of each leg may be thrown against one of the flange bases of the standard so as to prevent further outward spreading of the legs. The legs are braced together by suitable braces which 70 extend diametrically across from one leg to the opposite leg, the preferred form of bracing being shown in Figs. 1 and 6. A single bar or strip 15 is pivoted at 16 to one of the legs and hooks over a headed rivet 17 at 75 the other end. For the other two legs there are two brace pieces 18 which hook over the single brace 15 as is shown in Figs. 1 and 6. These braces prevent the legs from spreading; and it will be seen that braces lie in 80 the plane of the legs themselves, so that the braces and legs all lie directly beneath the upper curtain arms 20; and the compartments formed between these upper curtain arms will not be obstructed below by any 85 braces or legs projecting into the compartment spaces. Curtain arms 20 are pivoted at 21 to the upper end of standard 10 and normally extend horizontally outward as is shown in Fig. 1. These curtain arms are of 90 any convenient length and are supported by suitable braces 22. Braces 22 are preferably permanently pivoted at 23 to the standard and engaged with the arms 20 in any suitable releasable manner. I have shown 95 in Fig. 4 detail of the connection of these braces 22 with arms 20 comprising a key-hole slot 23 in the arms engageable with headed rivets 4 on the ends of the braces. But I may use a construction similar to Fig. 100 5 in place of this construction if so desired.

I provide four separate curtains 30 which are provided with suitable hooks 31, somewhat after the manner of a Pullman curtain, and each curtain hangs over the arms 20 in 105 such manner as is shown in Figs. 1 and 2, the ends of the curtains coming together at 32 where they can be separated for entry into the booths or compartments thus formed. The shape of the compartments 110 will be understood from the showing of Fig. 2. The hooks 31 directly support the

portions of the curtains which are adjacent the arms 20; and the outermost hooks 31 engage in notches 31^a in the arms to prevent the hooks sliding inwardly along the arms.

5 The remaining curtain portion is supported by having the upper edge stretched more or less tightly between the outer ends of the arms 20; the hooks 31 (shown farthest to the right in Fig. 1) and the hook 31^b holding this portion of the curtain to the arms. In each of the compartments thus formed there is supported a suitable member 35. This table member has a suitable hook 36 on one corner which hooks through an aperture 37 in one of the flanges of the upright standard 10. The outer end of the table is supported, one corner by a strap 38 which is pivoted at 39 to the arm 20 and which engages with the table member 35 in a manner similar to that shown in Fig. 5, the lower end of the strap being provided with a hook 40 adapted to engage a headed rivet 41 on the table member. The outer edge corner of the table is supported in a similar 20 member by the strap 38^a which engages a similar rivet on the table member in a similar manner. The remaining corner of the table is supported by a support 38^b which is pivoted at 39^b to the standard 10 and engages the table in the manner shown in Fig. 5. This makes the table members completely removable from the device.

When the booth has been used and it is desired to collapse and pack it, it is only 35 necessary to remove the table and then to remove the curtain. The braces 22 may be released from the arms 20, the braces and arms both being folded forwardly against the standard 10. The braces 15 and 18 of the 40 legs are released and folded slightly against the legs, the legs are then pulled downwardly and outwardly so that the upper ends of slots 13 will be engaged with rivets 12, when the legs may be turned upwardly 45 to lie flatly against the standard 10. When this is done a bundle of pieces slightly more than three feet in length is had of the structural parts of the device. The table members are relatively narrow and do not form

a large bundle. The curtains may be wrapped into comparatively small bundles and the whole structure may then be placed in a box or case ready for shipping.

Having described my invention, I claim;

1. A device of the character described, 55 comprising a single upright standard, bottom support and braces therefor, a plurality of outwardly extending arms foldingly attached to the upper end of the standard, folding braces for the arms, the arms being 60 arranged symmetrically with relation to the vertical standard axis, a plurality of table members, one for each of said arms, each table member being supported at one corner by attachment to the upright standard and 65 being arranged with one of its edges under and substantially parallel to its corresponding arm, a depending supporting strap attached to each arm and attached to the edge of the table member beneath, and diagonally 70 arranged straps attached to the respective arms and to the upright support and attached to and supporting the opposite edges of the corresponding table members.

2. A device of the character described, 75 comprising a single upright standard, bottom support and braces therefor, a plurality of outwardly extending arms foldingly attached to the upper end of the standard, folding braces for the arms, the arms being 80 arranged symmetrically with relation to the vertical standard axis, a plurality of table members, one for each of said arms, each table member being supported at one corner by attachment to the upright 85 standard and being arranged with one of its edges under and substantially parallel to its corresponding arm, and supporting straps attached to each arm and depending therefrom and attached to the corresponding 90 table member to support the same.

In witness that I claim the foregoing I have hereunto subscribed my name this 29th day of June 1912.

ELIZABETH J. DOUGLAS.
